TIMING DEVICE FOR CAP SPINNING MACHINES

Samuel A. Mansfield and Joseph L. Killoran,
Drummondville, Quebec, Canada, assignors to
Celanese Corporation of America, a corporation
of Delaware

Application July 7, 1936, Serial No. 89,436

7 Claims. (Cl. 33—132)

This invention relates to cap spinning machines and relates more particularly to a doffing timing device for such machines.

An object of the invention is the accurate timing of the filling of a number of bobbins operating on one artificial yarn spinning machine. Another object of the invention is the production, at the spinning machine, of packages of yarn each of which contains the same amount of yarn. 10 Other objects of the invention will appear from the following detailed description and drawings.

In the drawings, wherein like reference numerals refer to the same or similar elements;

Fig. 1 is a front view of a section of a spinning 15 machine constructed in accordance with this invention.

Fig. 2 is a sectional view, on an enlarged scale, of a part of the spinning machine.

Fig. 3 is a sectional view, taken on the line 20 3—3 of Fig. 2, and.

Fig. 4 is a sectional view taken on the line 4—4 of Fig. 2.

In the manufacture of artificial yarns, filaments are formed by extruding a solution of a 25 derivative of cellulose in a volatile solvent through suitable orifices in a spinning jet into a solidifying medium, and a yarn is formed from a group of continuous length filaments. The solidifying medium may be a gas as in the dry method of spinning, or a precipitating liquid as in the wet method of spinning. After the yarns are formed 30 they are drawn from the spinning cabinet or tank and wound into packages. In modern commercial practice, each spinning machine is equipped 35 with from 10 to 100 or more spinning jets and each spinning machine is usually provided with a take-up packaging device for each jet. The take-up packages are usually arranged in a row on one or both sides of the machine.

40 The device of the present invention has for its object the accurate timing of the filling of a number of bobbins operating on one spinning machine. Inasmuch as the speed of commercial electric motors will vary with the condition or 45 load of the driven machines, as well as with variations of frequency on the current supply line, the spinning machines with timing devices herein described have been developed so that the timing 50 device is controlled by the speed of the spinning machine itself. By employing spinning machines constructed in accordance with this invention, doffing of uniformly filled packages may be accomplished.

55 In accordance with our invention, we mount

on a spinning machine a novel timing device for indicating the amount of thread or yarn placed upon the take-up packages, which timing device accurately controls the actual amount of thread or yarn placed on the packages.

5 Referring to the drawings, the yarn is formed in a cabinet 2 containing suitable feed lines, pumps and spinning jets, not shown. The cabinet 2 also contains a suitable solidifying medium and guide rollers, not shown, to direct the yarn from the spinning jets to ports 3 in the cabinet. Rollers 4 are provided for drawing the threads or yarns from the cabinet and feeding them to take-up packages 5, which feed rollers are supported on a shaft 6. The thread or yarn is caused to be frictionally engaged by the feed rollers 4 by passing it one or more times around the roller. After leaving the feed roller, the thread or yarn passes through suitable guides, not shown, and is wound up on the bobbin 5. Both the shaft 6 10 supporting the feed rollers 4 and the bobbins 5 are driven at a substantially constant speed from any suitable source or sources of power.

15 The timing mechanism comprises a frame 11 formed of two right angle members 12 and 13 joined together by tie members 14. The frame 11 carries an upper bracket 15 and a lower bracket 16, which are adapted to support a screw 17 therebetween. The screw 17 is journaled in a bearing 18 in the lower bracket and a bearing 19 in the upper bracket. The lower and upper brackets may be secured to the frame 11 by means of tie bolts 21 which in the lower bracket are on either side of and in the upper bracket pass through 20 the slot 22 formed by the spacing of the angle members 12 and 13. Backing members 23 aid the tie bolts in gripping the angle members. If desired, the backing members 23 may be welded to the angle members 12 and 13 and the bolts placed in holes formed through the angle members and backing members. Fastened in any suitable manner on the angle member 13 is a 25 scale 24.

30 Mounted in the slot 22 formed by the angle members 12 and 13 is an adjustable tripping device 25. This tripping device comprises a bracket having a tongue 26, adapted for sliding engagement with the frame 11 in slot 22, and a clamping member 27 which may be provided with springs 35 28 tending to force the clamping member away from the inner face of the angle members 12 and 13 and the tongue 26. A screw 29 is provided 40 for clamping the tripping device onto the angle members. The bracket 25 carries a pointer 31 45

which cooperates with the scale 24 to allow an accurate setting of the tripping device. Mounted on the tripping device is a fixed stop or abutment 32.

5 Journaled in a housing 33 of the lower bracket is a shaft 34 which has a worm gear 35 attached thereto. On the outer end of the shaft 34 is a sprocket wheel or pulley 36 adapted to be driven from the shaft 6 by means of a belt or chain 37 10 and a sprocket wheel or pulley 38. Mounted on the screw 17 and in driving relation thereto is a gear 39 adapted to be rotated by the worm gear 35 which gear 39 in turn rotates the screw 17.

Screw 17 carries a rider which comprises a body 15 part or a casing 41 having non-threaded screw engaging bearings 42 and 43. To prevent rotation of the casing 41, the same is provided with a pin 44 which projects into the slot 22 formed of the angle members. A friction reducing roller 45 may 20 be provided on that part of the pin 44 contacting the sides of the slot 22.

In the casing 41 there is slidably mounted a threaded split nut 46 which can be thrown into or pulled out of engagement with the screw 17. 25 The nut 46 contains a pin 47 that acts as a cam follower in camways 48 formed in levers 49 and 51. Lever 49 is pivoted on a screw 52 on the casing 41 while the lever 51 is pivoted on a shaft 53 on the casing 41, the shaft 53 being held in a non-rotating relation to the lever 51. Mounted 30 on the lever 51 and shaft 53 is a housing 54 enclosing a mercury switch 55. The levers 49 and 51 are tied together by a roller 56 which operates against the fixed stop 32. The opposite ends of 35 levers 49 and 51 are tied together by a pin 57. The pin 57 and the casing 41 are connected by a snap action spring 58 which includes two telescoping members 59 and 61 and fastening means 62.

40 An electric cable 63 is adapted to connect the mercury switch 55 with a suitable signal, for example, a bell, a siren, a semaphore, a light or a combination of these, for instance, a red light provided with a siren connected in the red light circuit by means of a delayed action switch. Thus if the operator neglects to restart his timing device for more than 30 seconds the alarm sounds. For the purpose of setting the timing device the lever 51 terminates in a handle 64. 45 Thus, after the rider has fallen to the bottom the handle 64 will be in a raised position and the rider disengaged from the screw. After the operator has finished doffing he pushes the lever 51 downward effecting an engagement of the rider with the screw, which rider commences its slow movement upward. Alternatively, when the operator receives the signal he resets the lever 51 and starts doffing the bobbins.

The lower end of the casing 41 terminates in a 50 plunger 65. This plunger is made to weigh enough to ensure that the rider will fall promptly and with certainty. Adjustably mounted on the screw 17 by means of the nut 66 is a dash pot 67 adapted to cushion the fall of the rider.

65 In operation, the vertical screw 17 rotates continuously and the rider 41 is engaged with the screw by pressing lever or handle 64 downward. The rider slowly and continuously rides upward until the lever 51 or roller 56 meets the stop 32.

70 As the lever has a snap action it will jerk the nut 46 out of engagement with the screw as soon as the lever passes the center of its travel. As soon as the nut is disengaged the whole rider assembly falls under gravity while the electric switch 75 55 closes a circuit to a suitable visible or audible

indicator. When the operator receives the indication he re-sets the levers by means of handle 64 and starts doffing the bobbins. It will be seen that the rider will rise a definite distance for each revolution of the feed roller 4 which in turn represents a definite length of yarn passed to the bobbins 5. The ratio of the belt or chain device 37 and worm and gear drive 35-39 can be so chosen that one inch vertical rise of the rider will correspond to a definite number of revolutions of the feed roller, say one thousand. The stop 32 can be adjusted so as to trip the rider after any required number of revolutions of the feed roller. The pointer 31, which moves close to the scale 24, indicates at all times the number 15 of revolutions made since the start of the period and it can be used for setting the trip or stop 32.

When a bank of spinning machines have, for instance, 100 spindles on a side, the bobbins may not be doffed from the first to the last, but they 20 may be doffed in sections of say 20 bobbins. Thus the bobbin spindles may be portioned into, say, 5 sections along the length of the machine, and these sections numbered 1 to 5. When the signal is received by the operator he pulls down 25 handle 64 (which recommends the upward travel of the rider) and immediately proceeds to doff one section only. A few minutes after the completion of this doff the signal will again be given and the operator again restarts the rider on its 30 upward travel and immediately commences to doff the next section. In this method of operation the timer is set to operate at intervals corresponding to one-fifth of the desired bobbin filling time.

35 It will be seen that the device described above will designate the number of revolutions of the feed roller automatically. It is simple, accurate in its indication, free from trouble in operation, and inexpensive to make and install. It also has 40 the merit of being easily adjusted over a wide range.

45 This invention is applicable to the manufacture of packaging of any synthetic yarn, for instance, the yarns made of organic derivatives of cellulose or regenerated or reconstituted cellulose. Examples of organic derivatives of cellulose are the organic esters of cellulose such as cellulose acetate, cellulose formate, cellulose propionate and cellulose butyrate, while the ethers of cellulose are ethyl cellulose, methyl cellulose and 50 benzyl cellulose.

55 It is to be understood that the foregoing detailed description is given merely by way of illustration and that many variations may be made 55 therein without departing from the spirit of our invention.

Having described our invention, what we desire to secure by Letters Patent is:

1. A measuring device comprising a rotatable 60 screw, a rider mounted on said screw and adapted to be lifted from one end of said screw to the other end by the rotation of said screw, a member mounted on the rider and adapted to control the engagement and disengagement of said rider 65 with the screw, and tripping means adapted to engage said member at a predetermined point along the length of travel of the rider so as to disengage the rider from the screw and allow it to return by gravity to its starting position. 70

2. A measuring device comprising a rotatable screw, a rider mounted on said screw and adapted to be lifted from one end of said screw to the other end by the rotation of said screw, a pivoted member mounted on said rider and adapted to 75

control the engagement and disengagement of the rider with the screw, and tripping means adapted to engage said pivoted member at a predetermined point along the length of travel of the rider so as to disengage the rider from the screw and allow it to return by gravity to its starting position.

3. A measuring device comprising a rotatable screw, a rider mounted on said screw and adapted to be lifted from one end of said screw to the other end by the rotation of said screw, a pivoted member mounted on said rider and adapted to control the engagement and disengagement of the rider with the screw, and a fixed stop at a predetermined point along the length of the screw adapted to trip said pivoted member whereby the rider returns by gravity to its starting position.

4. A measuring device comprising a vertical rotatable screw, a rider mounted on said screw and adapted to be lifted from one end of said screw to the other end by the rotation of said screw, a pivoted member mounted on said rider and adapted to control the engagement and disengagement of the rider with the screw, a fixed stop at a predetermined point along the length of the screw adapted to trip said pivoted member whereby the rider falls to its starting position, and means for cushioning the fall of said rider.

5. A measuring device comprising a rotatable screw, a rider mounted on said screw and adapted to be lifted from one end of said screw to the other end by the rotation of said screw, a pivoted member mounted on said rider and adapted to control the engagement and disengagement of the rider with the screw, a fixed stop at a predetermined point along the length of the screw adapted to trip said pivoted member, whereby the rider returns by gravity to its starting position.

rider returns by gravity to its starting position, and an electric circuit including a mercury switch under the control of said pivoted member for signalling the tripping of said pivoted member.

6. A measuring device comprising a rotatable screw, a rider mounted on said screw and adapted to be lifted from one end of said screw to the other end by the rotation of said screw, means adapted to control the engagement and disengagement of the rider with said screw, said means comprising a lever pivoted on said rider and having a camway and a cam roller operating in said camway, and a stop at a predetermined point along the length of the screw for tripping said lever, the construction and arrangement being such that upon the tripping of the lever the cam roller causes the rider to become detached from the screw and return by gravity to its starting position.

7. A measuring device comprising a rotatable screw, a rider mounted on said screw and adapted to be lifted from one end of said screw to the other end by the rotation of said screw, means adapted to control the engagement and disengagement of the rider with said screw, said means comprising a lever pivoted on said rider and having a camway and a cam roller operating in said camway, a stop at a predetermined point along the length of the screw for tripping said lever, the construction and arrangement being such that upon the tripping of the lever the cam roller causes the rider to become detached from the screw and return by gravity to its starting position, and an electric circuit including a mercury switch under the control of said lever for signaling the tripping of said lever.
